LOCK HASP

Wallace E. Atkinson, Petersburg, Va., assignor to
Long Manufacturing Company, Inc., Peters-
burg, Va., a corporation of Virginia

Application May 29, 1951, Serial No. 228,903

5 Claims. (Cl. 292—281)

1

The present invention relates in general to improvements in lock hasps and more particularly is directed to lock hasps of the type having a projecting notched keeper tongue, designed specifically for use upon brief cases, trunks, travelling bags and the like.

Heretofore it has been common practice in making lock hasps of the type having a notched keeper tongue projecting perpendicularly from the hasp body and in planes parallel or transverse to the longitudinal medial axis of the hasp from a point spaced upwardly from the lower end thereof, to form the hasp body in the desired shape by stamping blanks of sheet material into the desired configuration for the body and securing thereto a separate projecting tongue by brazing, welding or like operations. These separate operations required to individually form the hasp body and tongue element into desired shape and securely attach the tongue to the hasp body in a manner that it will resist the severe stresses to which the keeper tongue is normally subjected, are relatively time-consuming and expensive.

Also, as is disclosed in the earlier Patent No. 1,951,551, issued March 20, 1934, to A. T. Long, a lock hasp having a rearwardly projecting eye catch or staple has been formed from a single blank of metal. In this construction, the blank is provided with lateral extensions projecting from the hasp body which are provided with slots adapted to receive a keeper bolt. These projections are bent in overlying relation with the rear face of the hasp body, and the extremities of the extensions having the slots therein are bent rearwardly at right angles to the plane of the hasp so that the slots are brought in alignment with each other to provide the staple. Such a construction, however, is attended by marked disadvantages, such as the difficulty of constructing dies which will provide accurate matching of the two separate lateral extensions and will bring the extensions into perfect alignment to form the complete staple extending in a plane intersecting the medial axis of the hasp body.

An object of the present invention, therefore, is to obviate the difficulties incident to separate production of the lock hasp and keeper tongue in the production of a finished lock hasp of this general character by forming the lock hasp and notched keeper tongue from a single blank of metal.

Another object of the present invention is the provision of an improved one-piece construction for a lock hasp of the type having a notched keeper tongue projecting in a transverse plane

2

from the inner surface thereof, in which the blank is arranged so that precise registry of mated parts which lends complexity to mass production dies is minimized.

Another object of the present invention is the provision of a novel lock hasp of the character having a notched keeper tongue projecting inwardly therefrom along a transverse plane perpendicular to the medial longitudinal axis of the hasp body by forming the lock hasp and keeper tongue in an integral manner from a single blank of metal which is characterized by exceptional strength and resistance to deformation by the stresses incident to use of such lock hasps.

Another object of the present invention is the provision of an improved one-piece construction for a lock hasp of the type having a notched keeper tongue projecting from the inner surface thereof in a transverse plane perpendicular to the longitudinal medial axis of the hasp body, which is formed from a single blank of metal with the parts bent in required position and interrelated in such a manner that each contributes to the strength and resistance to stress of the other parts.

Another object of the present invention is the provision of a novel lock hasp of the character having a notched keeper tongue projecting from the inner surface of the hasp body along a transverse plane perpendicular to the medial axis thereof by forming the lock hasp from a single piece of metal in which the parts are so arranged by suitable bending and shaping thereof to mutually contribute to the strength of each of the parts and to leave no exposed unattractive surfaces or edges.

Another object of the present invention is the provision of a novel lock hasp of the type having a rearwardly projecting notched keeper tongue, which is formed from a single blank of metal with the parts so arranged by suitable bending and shaping thereof to produce a hasp of more attractive and advantageous arrangement of parts, preserving an apparent uniformity of thickness of the hasp body, eliminating exposed fold ends and edges, and providing a smooth rear contact surface devoid of abrupt variations in thickness to permit accurate mating of the hasp body with the lock plate.

Other objects, advantages and capabilities of the present invention will become apparent from the following detailed description, taken in conjunction with the accompanying drawings, wherein only a preferred embodiment of the invention is shown.

In the drawings:

Figure 1 is a front elevation of a lock hasp of the type having an integral keeper tongue projecting from the inner surface of the hasp body in a transverse plane perpendicular to the medial axis of the body, constructed in accordance with the present invention;

Figure 2 is a plan view of the blank of sheet metal material from which the lock hasp is formed;

Figure 3 is a rear elevation of the lock hasp body showing only the lower portion thereof, illustrating the specific arrangement of the projecting notched keeper tongue on the hasp body in the finished product;

Figure 4 is a vertical section of the lower portion of the lock hasp body taken along the lines 4-4 of Figure 3;

Figure 5 is a transverse section illustrating the interrelation of the projecting keeper tongue with the bent flanges of the lock hasp body, taken along the lines 5-5 of Figure 3; and

Figure 6 is a horizontal transverse section of the lower portion of a modified form of lock hasp body, showing struck over flange portion for retaining the tongue plate in position.

Referring particularly to the drawings, wherein like reference characters designate corresponding parts throughout the several figures, the hasp body, generally indicated by the reference character 10, is adapted to be hingedly or pivotally coupled to a hasp plate 12 by means of a hidden pintle or pivot pin 14 which extends through a sleeve head 16 formed from the hasp body 10 by rolling a portion of the upper end of the hasp body into tubular form.

The hasp plate 12 is of the conventional type provided with apertures for mounting the hasp plate on a suitable trunk, traveling bag or the like, by means of screws. The sleeve head 16 is located between corresponding rolled ear sockets or sleeve formations 18 which are formed integral with the hasp plate 12 and into which the ends of the pivot pin 14 extend to provide the pivotal coupling between the hasp body 10 and the hasp plate 12.

The opposite longitudinal edges of the hasp body 10 are each bordered by a rearwardly projecting flange 20 which is integrally formed with the hasp body 10. Tightly secured between the flanges 20, at the lower end of the hasp body, is the tongue plate 22 which, as illustrated in Figure 2, is formed integral with the hasp body 10. The notched keeper tongue 24 is formed integrally with the tongue plate 22, and extends from the end thereof at right angles to the inner surface of the hasp body 10 in a plane perpendicular to the longitudinal medial axis of the hasp body. The tongue is provided with notches 25 in the opposite side edges thereof adjacent the throat of the tongue for engagement by keeper portions of a suitable lock (not shown) with which the hasp may be used.

The single blank of sheet metal from which the lock hasp is formed is illustrated particularly in Figure 2, the illustration in Figure 2 being provided with dotted lines 26, 26', 27 and 28 illustrating, respectively, the bend or fold lines along which the tongue plate 22 is bent back into overlying relation with the rear surface of the hasp body 10, the longitudinal edge flanges 20 are bent into rearwardly projecting substantially perpendicular relation with the rear surface of the hasp body, and the tongue 24 is bent into right angular relation with the tongue plate 22

projecting rearwardly from the overlying tongue plate 22 and hasp body 10.

Projecting ears 29 are formed at the throat or base of the tongue plate 22 adjacent the hasp body 10 to cover the lower edges or ends of their adjacent flanges 20, the ears 29, for this purpose, being cut back at their upper edges adjacent flanges 20 to a point in line with the bend or fold lines 27.

The lock hasp is formed by bending notched tongue portion 24 forward toward the front of the lock hasp along the bend line 28 into a position lying at right angles to the tongue plate 22. The tongue plate 22 is then folded rearwardly through an arc of one hundred eighty degrees along fold lines 26 and 26' into a position overlying and in intimate contact with the rear surface of the hasp body 10, as illustrated in Figure 4. The longitudinal edge flanges 20 are then bent rearwardly along fold lines 27 through an arc of approximately ninety degrees into a position extending perpendicular to the rear face of the lock hasp 10 and intimately engaging the sides of the tongue plate 22. Suitable adhesives 25 may be disposed between the overlying faces of the tongue plate 22 and the hasp body 10, and the side edges of the tongue plate 22 and adjacent portions of the flanges 20. In this position the laterally projecting ears 29 at the throat or base of the tongue plate 22 will be extending laterally in intimate overlying relation with the otherwise exposed lower edges of the flanges 20. The outer ends of the laterally extending ears 29 disposed in covering relation with the lower ends 35 of the flanges 20 may then be finished off or burnished to form a round corner 29a.

In the modified form illustrated in Figure 6, the inner edges of the flanges 20 along the lower portion thereof are struck over the adjacent portions of the tongue plate 22 forming projections 30 overlying the lateral edge portions of the tongue plate 22 to aid in maintaining the tongue plate in overlying relation with the hasp body in opposition to deforming stresses imposed on the tongue plate in use.

It will be readily seen that the lock hasp may be conveniently stamped out of a single piece of metal in an approximate manner to form an integral lock hasp of the type having a rearwardly projecting notched keeper tongue extending in a plane perpendicular to the longitudinal medial axis of the hasp body, and in which the disposition of the right angular flanges 20 intimately abutting the sides of the tongue plate 22 assist in maintaining the keeper tongue in proper position and facilitate the resistance to the stresses imposed during use of the lock hasp. As a result, this lock hasp may be more economically produced than can be done where the parts are separately formed and secured by welding, riveting or the like.

While but one specific embodiment of the invention has been particularly shown and described, it is distinctly understood that the invention is not limited thereto, but that various modifications may be made without departing from the spirit and scope thereof, and it is desired, therefore, that only such limitations shall be placed thereon as are imposed by the prior art and are set forth in the appended claims.

What is claimed is:

1. A hasp for locks formed of a single blank of sheet material and comprising an elongated body having a tongue plate comprising a turned back portion of one end of said body disposed

in intimate overlying relation with the rear face of said body, turned flanges extending along each longitudinal edge of said body, said flanges being bent into perpendicular relation to said body to project rearwardly therefrom, and a keeper tongue formed from an outturned terminal portion of said tongue plate projecting perpendicularly from the rear face of said body, said tongue having notches formed in the opposite lateral edges thereof for cooperation with the keeper element of a lock.

2. In a hasp for locks formed of a single blank of sheet material, the combination set forth in claim 1, wherein said tongue plate is tightly pressed between said flanges and frictionally gripped thereby.

3. A hasp for locks formed of a single blank of sheet material and comprising an elongated body having a tongue plate comprising a turned back portion of one end of said body disposed in intimate overlying relation with the rear face of said body, turned flanges extending along each longitudinal edge of said body, said flanges being bent into perpendicular relation to said body to project rearwardly therefrom, a keeper tongue formed from an outturned terminal portion of said tongue plate projecting perpendicularly from the rear face of said body, said tongue having notches formed in the opposite lateral edges thereof for cooperation with the keeper element of a lock, and laterally projecting ears formed on the opposite edges of said tongue plate adjacent the base thereof bent into covering relation with the exposed adjacent ends of said flanges to form finished corners at the terminal corners of said hasp body.

4. A hasp for locks formed of a single blank of sheet material and comprising an elongated body having a tongue plate comprising a turned back portion of one end of said body disposed in intimate overlying relation with the rear face of said body, turned flanges extending along each longitudinal edge of said body, said flanges being bent into perpendicular relation to said body to project rearwardly therefrom and frictionally grip the longitudinal edges of said overlying

tongue plate, and a keeper tongue formed from an outturned terminal portion of said tongue plate projecting perpendicularly from the rear face of said body, said tongue having notches formed in the opposite lateral edges thereof for cooperation with the keeper element of a lock, the longitudinal edges of each of said flanges being struck over the adjacent edge portions of said tongue plate frictionally held therebetween to facilitate retention of said tongue plate in overlying relation with said body.

5. A hasp for locks formed of a single blank of sheet material and comprising an elongated body having a tongue plate comprising a turned back portion of one end of said body disposed in intimate overlying relation with the rear face of said body, turned flanges extending along each longitudinal edges of said body, said flanges being bent into perpendicular relation to said body to project rearwardly therefrom and frictionally grip the longitudinal edges of said overlying tongue plate, a keeper tongue formed from an outturned terminal portion of said tongue plate projecting perpendicularly from the rear face of said body, said tongue having notches formed in the opposite lateral edges thereof for cooperation with the keeper element of a lock, the longitudinal edges of each of said flanges being struck over the adjacent edge portions of said tongue plate frictionally held therebetween to facilitate retention of said tongue plate in overlying relation with said body, and laterally projecting ears formed on the opposite edges of said tongue plate adjacent the base thereof bent into covering relation with the exposed adjacent ends of said flanges to form finished corners at the terminal corners of said hasp body.
